Primary Examiner — Susan M Lee*Assistant Examiner* — Linda G Brooks(74) *Attorney, Agent, or Firm* — Boyle Fredrickson, S.C.(57) **CLAIM**

The ornamental design for a bicycle cog, substantially as shown and described.

DESCRIPTION

FIG. 1 is a perspective view of a bicycle cog according to the present invention;

FIG. 2 is a right side elevation view of the bicycle cog shown in FIG. 1;

FIG. 3 is a front elevation view of the bicycle cog shown in FIG. 1;

FIG. 4 is a top plan view of the bicycle cog shown in FIG. 1; and,

FIG. 5 is a left side elevation view of the bicycle cog shown in FIG. 1.

The broken lines represent environmental structure and form no part of the claimed design.
